FOUNDATION GARMENT

Carl Redman Glines, Hamden, Conn., assignor to
Charis Corporation, a corporation of New York

Application March 17, 1945, Serial No. 583,241

1 Claim. (Cl. 2—43)

1

This invention relates to foundation garments and particularly to the type of garment known as a "panty girdle" where the construction combines a girdle member with short integral leg members.

With the construction of this invention the garment consists of a plurality of fabric panels stitched together longitudinally to form the girdle portion of the garment and stitched along portions of the base edges to form the leg members.

The front section consists of at least three panel members, the center panel of which is provided with a wide top portion tapering longitudinally to a narrow base section and terminating in a narrow band extension integral with the panel itself and having parallel sides. The tapering sides of the center panel and the corresponding portions of the adjacent panels are disposed so that when the panels are stitched together the tapered seams are adapted substantially to follow the groin lines of the wearer with the band extension fitting across the crotch area. The leg members are formed by stitching together portions of the base edges of the panels of the front and back sections (including the entire base edge of the center front panel) along a common slightly arcuate line determined by the base edge of the center panel of the front section.

Preferably, the panels of the back section are joined longitudinally so that when portions of the base edges of the front and back panels are stitched together the longitudinal seam of the back section is centrally disposed and meets the arcuate seam at a point within the base edge of the narrow band extension.

In adjusting this garment the wearer quite naturally grasps the top edge of the front section and pulls upwardly and outwardly along the lines formed by the tapered seams of the front section. In this manner the force applied to the garment is applied perpendicularly to the stitching across the seams and is distributed along the entire length of the tapered seams. Such a construction obviates distortion in the shape of the garment and, by distributing the stress along the length of the seam, the stitching is not put under too great a strain in a restricted area.

In adjusting the garment the wearer may readily obtain a snug fitting adjustment, particularly in the crotch area, by gripping the top edges of the front of the garment and pulling upwardly and outwardly substantially simultaneously along the lines of the tapered seams. The resultant force, directed almost wholly on the narrow band

2

extension, provides immediate and effective adjustment of the garment in position.

Where there is relative movement of the panel members, particularly in sitting and walking, the band extension provides a hinged effect along each lengthwise seam: each of the leg members is then free to move relative to the band extension. By reason of this construction the garment is anchored on the body in such a manner as not to interfere with body action, nor will it ride up on the figure to create discomfort, especially between the thighs in the crotch area. Accordingly, the garment fits snugly at all times without "pulling."

The fabric panel members may be made with either elastic or inelastic cloth or knit material; and the garment may consist entirely of panels of such elastic or inelastic material or may combine both types of material. Similarly, the garment may be either boned or not boned; and may be worn with or without garters.

In the accompanying drawing a specific embodiment of this invention is shown, and, of course, variations in the construction may be made within the concept of the invention. In the drawing: Fig. 1 is a front view of the foundation garment; Fig. 2 is a back view; Fig. 3 is a side view, and Fig. 4 is a front view illustrating the garment disposed in sitting position.

The front section 10 is shown consisting of a longitudinally tapered center panel 12 with two adjacent outer panels 14 and 16. The band extension 18 having parallel sides 19 and 21 is shown in Fig. 4 and as may be seen the base edge 20 of the band extension determines the slightly arcuate line 29 along which portions of the base edges of panels 14 and 16 are joined to the corresponding portions of the base edges of the back panels. The parallel sides 19 and 21 of the band extension 18 are of the same length (determined by the size of the garment) to provide equal hinge action along both sides of the crotch and to permit the body of the wearer to sit properly in the garment.

The two elastic side panels 22 and 24 are intermediate the front and back sections and ordinarily their base edges 23 and 25 are unattached. As can be seen from the drawing, the openings of the leg members 36 and 38 are formed by the unattached base portions of the front, side, and back panel members and are of sufficient length to enclose the thighs and give the garment proper purchase on the body.

The back section consists, in this case, of two back panels 26 and 28. In Fig. 4 the central longitudinal seam 27 of back panels 26 and 28 is shown disposed so that this seam meets the arcu-

ate seam 29 on the base edge of the band extension at a point intermediate the parallel sides 19 and 21. Such construction eliminates crowding of the seams and permits the hinged effect along the sides 19 and 21 freely to take place when there is relative movement between the members.

A zipper opening 34 is provided longitudinally along one of the front panels and garter supports 37 may be provided as shown.

What I claim is:

A foundation garment having a girdle portion and integral leg members comprising a plurality of fabric panels joined together longitudinally along seams with stitching perpendicular to the seams to form a girdle portion and stitched together along portions of the base edges of said panels to form leg members, the front section of the garment consisting of at least three panels the center panel of which has a relatively wide top edge with sides tapering longitudinally along straight lines from the wide top edge to a nar-

row base portion terminating in a narrow band extension having parallel sides of equal length integral therewith and aligned with the center line of the converging panels and adapted to fit across the crotch area, the base edge of said band extension being joined to the base end of the back panel members, the tapered sides of the center front panel when stitched to the corresponding sides of the adjacent panels forming seams which are disposed so as substantially to follow the groin lines of the wearer of the garment whereby force applied upwardly and outwardly at the top of said seams is applied perpendicularly to the stitching of said seams and is distributed along substantially the entire length of said seams, the parallel seams of the band extension being adapted to act as hinge members to obviate "pulling" of the garment when there is relative movement between such panel members.
